UNITED STATES PATENT OFFICE.

FRANK B. MELVILLE, OF MINNEAPOLIS, MINNESOTA, ASSIGNOR OF ONE-HALF TO RALPH REES, OF SAME PLACE.

BUSTLE.

SPECIFICATION forming part of Letters Patent No. 372,633, dated November 1, 1887.

Application filed June 10, 1887. Serial No. 240,872. (No model.)

To all whom it may concern:

Be it known that I, FRANK B. MELVILLE, a citizen of the United States, residing at Minneapolis, in the county of Hennepin and 5 State of Minnesota, have invented certain new and useful Improvements in Bustles, of which the following is a specification.

My invention relates to bustles having pendant coil-springs in the pockets of a fabric, 10 and it is the object of the invention to provide a bustle that will be comfortable for the wearer, while serving to hold the garments in a shapely form; and the improvements consist in the combinations and arrangements of 15 parts, hereinafter fully described, and particularly pointed out in the claims.

The improvements are illustrated in the accompanying drawings, in which—

Figure 1 is a front view of a bustle embodying my invention. Fig. 2 is a side view of the same. Fig. 3 is a transverse section on the line $x x$ of Fig. 2, and Fig. 4 is a detached view of one of the spring-fasteners and one of the springs.

25 In the drawings, A designates a fabric, of cotton or other suitable material, provided with pockets for receiving the coil-springs.

$a a$ are the pockets, formed at proper intervals by folding the fabric at intervals and sewing together the doubled portions on parallel lines to produce substantially parallel tubular pockets. The upper ends of the pockets, as 30 also the fabric between them, are gathered and secured to a band, B.

35 $c c$ are coil-springs, slightly convoluted at their upper ends to fit the contracted upper ends of the pockets and give a rounding shape to the top of the bustle. The springs are inserted in the pockets a from below, and fit 40 snugly in them when in place. The upper ends of the wires of the springs are bent over to form eyes c' , and small snap-hooks d are secured in the pockets to the band B, and the springs are suspended by hooking their eyes 45 into the snap-hooks. The springs can readily be withdrawn when desired by disconnecting them from the hooks by pressing upon the snap-hooks from the outside.

The gathering of the upper end of the fabric and the expansion of its pockets by the springs cause the bustle to assume a curved

form; and to prevent the end pockets from turning inward too far, and also to prevent distortion by any unequal pressure of the springs, and thus to preserve a symmetrical 55 contour of the bustle, there is provided a band, b , secured to the end pockets and extending around over the intermediate pockets. Along the adjacent surfaces of the end pockets are secured strips e , of suitable fabric, provided 60 with eyes e' , and in the eyes is inserted a lacing-cord, f , which, while affording a means for regulating the distance between the end coils to adjust the bustle to the person of the wearer, and a means for regulating the expansive 65 effect of the bustle upon the draperies it supports, serves also to prevent the inner coils from pressing directly against the person.

Triangular-shaped side pieces, D, having eyes i along the inner and upper edges, are 70 adjustably connected to the pockets a and band B by means of eyes i' in strips h , secured to the pockets, eyes i^2 in the band, and laces l , inserted in the eyes. On the outside of the pieces D are pockets m in diagonal position, 75 and in the pockets are wire coils n , preferably of double helical form, having their widest expanse at the middle. These side pieces, with their coils, serve to hold out the side drapery of the wearer and prevent any depressed appearance of the garments at the sides.

What I claim is—

1. A bustle composed of a fabric having parallel pockets formed on one side thereof, the said pockets having their upper ends gathered and the fabric having its upper end gathered, a waistband secured to the upper end of the fabric and pockets, coil-springs in said pockets adapted to distend them laterally, the distance between the centers of 85 the distended pockets being greater than the distance between the attaching-points of the said pockets to the fabric, whereby the bustle is caused to assume a laterally-curved shape, lacing-eyes and a lace for adjustably connecting the sides of the bustle, and side pieces connected to the sides of the bustle and to the waistband, substantially as set forth.

2. A bustle composed of a fabric having parallel pockets formed on one side thereof, 90 and having their upper ends contracted and the fabric having its upper end gathered, a

waistband secured to the upper end of the fabric and pockets, coil-springs in said pockets adapted to distend them laterally, the distance between the centers of the distended 5 pockets being greater than the distance between the attaching-points of the said pockets to the fabric, whereby the bustle is made to curve laterally, a band exterior to the pockets and having its ends secured to the 10 sides of the bustle to prevent unequal distention of the pockets, and a lace for adjustably connecting the sides of the bustle, substantially as set forth.

3. In combination, in a bustle, a fabric having 15 pockets formed on one side thereof, and having their upper ends contracted and the fabric having its upper end gathered, a waistband se-

cured to the upper end of the fabric and pockets, coil-springs in the pockets adapted to distend them laterally, the distance between the centers 20 of the distended pockets being greater than the distance between the attaching-points of the said pockets to the fabric, whereby the bustle is made to curve laterally, lacing-eyes and a lace for connecting the sides of the bustle, a band exterior to the pockets for preventing distortion of the pockets, and side pieces 25 connected to the sides of the bustle and waistband, substantially as set forth.

FRANK B. MELVILLE.
